UNITED STATES PATENT OFFICE

170,960

PHOTOGRAPHIC ENLARGER OR
SIMILAR ARTICLE

Robert M. Barth, Pelham Manor, and Harold G. Bergstrom, New Rochelle, N. Y., assignors to The F R Corporation, New York, N. Y., a corporation of New York

Application July 29, 1953, Serial No. 26,179

Term of patent 14 years

(Cl. D61—1)

To all whom it may concern:

Be it known that we, Robert M. Barth and Harold G. Bergstrom, both citizens of the United States, and residents, respectively, of Pelham Manor, New York, and New Rochelle, New York, have invented a new, original, and ornamental Design for a Photographic Enlarger or Similar Article, of which the following is a specification, reference being had to the accompanying drawing, forming a part hereof, in which

Figure 1 is a perspective view of a photographic enlarger, or similar article, showing our new design;

Figure 2 is a side elevational view thereof; and
Figure 3 is a front elevational view thereof.

We claim:

The ornamental design for a photographic enlarger or similar article, as shown.

ROBERT M. BARTH.

HAROLD G. BERGSTROM.
